UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed June 30, 1922. Serial No. 572,064.

To all whom it may concern:

Be it known that I, CHARLES DAVID BONSALL, a citizen of the United States, and a resident of the city of Pittsburgh, county of Allegheny, and State of Pennsylvania, have invented a certain new and useful Improvement in Car Roofs, of which the following is a specification.

This invention relates to car roofs of the all-steel riveted-up type wherein the roofing sheets extend from side plate to side plate of the car and are rigidly secured thereto and are rigidly connected to each other by upstanding water proofing seams or joints that function as carlines.

One of the principal objects of the present invention is to increase the strength and rigidity of the roof by improving the sectional shape and arrangement of the seam or joint construction. Other objects are to simplify the construction of the roof and to cheapen the cost of manufacture. The invention consists principally in the improved weather proofing seam or joint construction hereinafter shown and described; and it also consists in the parts and arrangements and combinations of parts hereinafter described and claimed.

In the accompanying drawing, wherein like symbols refer to like parts wherever they occur,

Fig. 1 is a plan view of a portion of a car roof embodying my invention;

Fig. 2 is an enlarged transverse section through one half of the roof, the section being taken between seams on the line 2—2 in Fig. 1;

Fig. 3 is a vertical cross-section through one of the seams at the ridge on the line 3—3 in Fig. 2;

Fig. 4 is a similar section through the seam midway of the ridge and eaves on the line 4—4 in Fig. 2;

Fig. 5 is a similar section through the seam at the side plate on the line 4—4 in Fig. 2; and

Figs. 6, 7 and 8 are vertical cross-sections through a modified form of seam construction, the sections being taken at points corresponding to the lines of sections 3—3, 4—4 and 5—5 respectively, in Fig. 1.

The roof shown in Figs. 1 to 5 of the accompanying drawing comprises metallic load sustaining roof sheets 10, which extend transversely of the car from eaves to eaves thereof and have drip-flanges 11 depending from their eaves ends. The roof sheets are supported at their eaves ends on the outwardly projecting uppermost flanges of angle bar side plates 12 and are suitably secured thereto by rivets 13. The side marginal portion of each roof sheet is raised above the body portion of the sheet preferably in the form of a seam flange A of substantially inverted L-shaped section; that is, said pressed up marginal portion has a nearly vertical web portion 14 at the top of which is an outwardly projecting lateral flange 15.

The web portions 14 of the side marginal flanges or ribs A of each sheet converge towards each other on each side of the ridge towards the eaves and are deepest at the ridge and gradually decrease in depth towards the eaves where they merge abruptly into the plane of the sheet; and the lateral flanges 15 have a minimum width at the ridge and widen gradually towards the eaves where they merge abruptly into the plane of the sheet. Thus, the roof sheet flanges or stiffening ribs A decrease in depth and increase in width uniformly from the ridge towards the eaves and have downwardly curved eaves end portions that merge into the plane of the sheets where the eaves ends thereof are turned down to form the drip-flanges 11. It is noted that the reverse taper of the portions 14 and 15 of the side marginal flanges of the roof sheets permits the use of all of the metal contained in the rectangular sheet blank without the expense of trimming the blank to a special shape before pressing.

In assembling the roof sheets upon the car a slight space is left between the side marginal flanges of adjacent sheets; and said flanges are covered by caps 16, preferably of heavier gage metal than said roof sheets. These caps are also pressed from blanks of uniform width and are of inverted channel shape section; that is, each cap has a horizontal web portion, that rests on

the seam flanges of adjacent sheets, and depending side marginal flanges that bear flatwise against the web portions of said seam flanges. The caps are rigidly secured 5 to the outwardly flanged portion 15 of the seam flanges or ribs of adjacent sheets by two rows of vertical rivets 17 to form rigid water proofing seams or joints. The web portion of the caps have a minimum width 10 at the ridge and widen gradually to the eaves, whereby the depending side marginal flanges of said cap diverge from each other on opposite sides of the ridge towards the eaves at angles that correspond to the angles 15 of the web portions 14 of the seam flanges that are embraced by said caps.

The caps extend from eaves to eaves of the car and have downwardly curved eaves end portions that correspond to the downwardly 20 curved eaves end portions of the roof sheet flanges and are formed with depending eaves flanges 18 that overlap the joints between the depending drip-flanges 11 of adjacent roof sheets. As the width of the caps increase 25 from the ridge towards the eaves, there is a corresponding decrease in the depth of the depending side flanges of said caps from the ridge towards the eaves. At points adjacent to the eaves the side flanges 30 of the caps reach the plane of the sheets and are turned outwardly to form lateral flanges 19; and the surplus of metal resulting from the downwardly curved eaves end portions of the caps is utilized in increasing the width 35 of said flanges towards the ends of the caps.

Running boards 20 extend longitudinally of the car at the ridge and are securely bolted to the upwardly offset marginal flanges of running board saddles 21, which 40 rest on and are rigidly secured to the tops of the seams by the rivets 17 that secure the caps 16 to the roof sheet flanges.

In the modified seam or joint construction shown in Figs. 6 to 8, the roof sheet flanges 45 A¹ gradually decrease in depth from ridge to eaves, but said flanges, together with the caps 16^a are of substantially uniform width from eaves to eaves. The caps 16^a are similar to the caps 16; that is, the caps 16^a are of 50 substantially channel-shaped section and have downwardly curved eaves end portions provided with depending eaves flanges; but the caps 16^a are of substantially uniform width and depth and have lateral flanges 19^a 55 at their eaves ends that are wider than the corresponding flanges 19 of the caps 16 and are rigidly secured to the adjacent body portions of the sheets by the rivets 13 that secure the eaves ends of said sheets to the side 60 plates. This form of seam or joint construction necessitates shearing of the sheet and the cap blanks to a special shape before pressing.

By the arrangement described, the roof 65 sheets are rigidly secured together by caps

that cooperate with the raised seam flanges or strengthening ribs of the roof sheets to form rigid water proofing seams or joints of inverted channel shaped section which act after the manner of carlines to increase the 70 load carrying capacity of the roof and serve as frame members to brace and stiffen the car-body. It is noted that the strength and rigidity of the roof joints is increased by the use of caps of heavier gage than the roof 75 sheets. It is also noted that the depending side flanges of the caps are adapted to bear against the side flanges of the roof sheets, whereby the friction between the contacting 80 surfaces of the caps and roof sheet flanges resists relative sliding of the caps and seam flanges and has the effect of increasing the resistance to stresses that tend to shear the securing rivets. Another advantage resulting from the use of the caps is that it enables 85 a wide joint to be obtained without the use of wide roof sheet flanges.

The invention is not restricted to the particular shapes and arrangements of parts shown in the drawing. 90

What I claim is:

1. A rigid car roof comprising metal roof sheets whose adjacent marginal portions are spaced apart and provided with upstanding flanges, and cap strips connecting the spaced 95 upstanding flanges of adjacent sheets and positively secured thereto to form hollow upstanding seams or joints.

2. A rigid car roof comprising self-sustaining metal roof sheets whose adjacent marginal portions are spaced apart and provided with upstanding flanges, and cap strips of varying depth embracing the spaced upstanding flanges of adjacent sheets and rigidly secured thereto to form hollow upstanding seams or joints of varying depth. 100

3. A rigid car roof comprising metal roof sheets whose adjacent margins are spaced apart and provided with upstanding flanges that are narrowest midway of their ends, 110 and cap strips connecting the spaced upstanding flanges of adjacent sheets and rigidly secured thereto to form hollow upstanding seams or joints that are narrowest midway of their ends. 115

4. A car roof comprising roof sheets extending from eaves to eaves, the side marginal portions of said sheets being disposed above the body portions of the sheets, and cap strips rigidly connecting the raised side 120 marginal portions of adjacent sheets and cooperating therewith to form hollow seams or joints that function as carlines.

5. A car roof comprising roof sheets extending from eaves to eaves of the car and rigidly secured thereto, the side marginal portions of adjacent sheets being spaced apart and formed into raised flanges of substantially inverted L-shaped section, and an inverted channel shaped cap embracing the 125

marginal flanges of adjacent sheets and rigidly secured thereto to form hollow weather proofing joints.

6. A joint cap for a car roof comprising a strip of channel-shaped section whose width increases from its middle towards its ends.

7. A joint cap for car roof comprising a

strip of channel-shaped section of correspondingly increased width and decreased depth from the ridge towards the eaves. ¹⁰

Signed at New Kensington, Pa., this 26th day of June, 1922.

CHARLES DAVID BONSALL.

Certificate of Correction.

It is hereby certified that in Letters Patent No. 1,482,782, granted February 5, 1924, upon the application of Charles David Bonsall, of Pittsburgh, Pennsylvania, for an improvement in "Car Roofs," an error appears in the printed specification requiring correction as follows: Page 2, line 103, claim 2, strike out the words "of varying depth" and insert the same to follow after the word "flanges", line 102; and that the said Letters Patent should be read with this correction therein that the same may conform to the record of the case in the Patent Office.

Signed and sealed this 18th day of March, A. D., 1924.

[SEAL.]

KARL FENNING,
Acting Commissioner of Patents.
